UNITED STATES PATENT OFFICE.

HENRY J. STAMBAUGH, OF TROY, NEW YORK, AND GEORGE M. McCANN, OF WASHINGTON, DISTRICT OF COLUMBIA, ASSIGNEES TO UNITED STATES ORDNANCE COMPANY, OF WASHINGTON, DISTRICT OF COLUMBIA, A CORPORATION OF VIRGINIA.

BREECH MECHANISM.

Application filed December 31, 1923. Serial No. 683,753.

To all whom it may concern:

Be it known that we, HENRY J. STAMBAUGH and GEORGE M. McCANN, citizens of the United States, and residents of Troy, in the county of Rensselaer and State of New York, and Washington, in the District of Columbia, respectively, have invented certain new and useful Improvements in Breech Mechanisms, of which the following is a specification.

Our invention relates to breech mechanisms of the general type shown in U. S. Patent No. 1,348,594, granted to us August 3, 1920 and wherein provision is made for imparting motion of translation to the breech plug with respect to the carrier to get the gas check into and out of its seat, so that the slope of said seat can be materially reduced and yet provide sufficient clearance for swinging the breech plug.

Objects of our invention are to provide an improved construction for imparting motion of translation to the breech plug which can be incorporated in existing types of guns at a relatively small cost and with a minimum amount of alteration and additional equipment; which will control the movements of the plug during translation in a highly efficient manner; which will operate to impart motion of translation to the plug in varying ratio with respect to the plug's rotation and vice versa; in which all elements of the translating structure move relatively to the gun and carrier during translation; in which the movement of all the elements of the translating structure relative to the gun and carrier is effected by rotation of the plug; which can be employed as a component part of the breech mechanism actuating shaft, and when so employed operable either through the shaft or through the rotation of the plug when such rotation is accomplished independently of the shaft; and which will enable the translation of the plug to be effected with great ease.

In the drawings chosen to illustrate our invention the scope whereof is pointed out in the claims—

Figure 1 is a rear elevation of a gun constructed in accordance with our invention, with the breech fully closed;

Figure 2, a section on the line 2—2 of Fig. 1;

Figure 3, a section on the line 3—3 of Fig. 1; 55

Figure 4, a section on the line 4—4 of Fig. 1;

Figure 5, a view similar to Fig. 4 showing the position of the parts just before the breech plug threads engage the screw box 60 threads; and

Figure 6, a view similar to Figure 4 showing the position of the parts when full unlocking rotation has been imparted to the breech plug. 65

Referring to the drawings A is the gun, B the breech plug, and C the swinging carrier which embodies a tubular spindle C'. The plug is mounted for both movements of rotation and translation with respect to the carrier. Extending axially through the plug B and keyed to the spindle C' for limited sliding movement relative to the plug is the stem 10 of a mushroom 11 and confined between the plug B and the mushroom 11 is a 70 gas check 12 of the "De Bange type".

In the adaptation of our invention as illustrated the locking and unlocking rotation of the plug B is designed to be directly effected by rotation of a crank shaft 12', mounted in the carrier and operated through the medium of a suitable handle 13. Fixed to the shaft 12' is a crank arm 14 having a crank pin 15 engaged with a cross head 16 slidably mounted in a rearward extension 17 of the plug for movement longitudinally thereof and whereby rotation of the shaft 12' will effect rotation of the plug B. 80

The locking rotation of the breech plug B is also adapted to be initiated by energy 90 stored in the swinging breech mechanism and to this end we rotatably mount on the spindle C' a sleeve 18 upon which the rear portion of the plug B has bearing and provided on the rear end of this sleeve are diametrically oppositely disposed arms 19 and 20, 95 the free ends of which are turned forwardly as at 21 and project respectively into recesses 23 formed in the plug B. The forwardly turned portions 21 of the arms 19 and 20 each have mounted therein a pintle 22 and upon each pintle is rotatably engaged a roller 23' and these rollers are adapted to contact respectively with cams 24 formed on the gun A for the purpose of initiating locking 100 rotation of the plug B. In this connection 105

it will be observed that owing to the interlocked relation between the outer ends of the arms 19 and 20 and the plug any rotation imparted to said arms and the sleeve 18 will 5 in turn be imparted to the breech plug B. By providing diametrically opposite disposed rollers on the operator we render the action of the parts more balanced. It will also be noted that the construction herein 10 described and illustrated for initiating locking rotation of the plug and initiating opening movement of the carrier during unlocking rotation of the plug is fully covered in U. S. Patent No. 1,348,594 granted to us 15 August 30, 1920.

The mechanism for effecting translation of the plug B embodies an arm 25 fixed on the shaft 12' which carries a roller 26 adapted to coact with the walls of a cam groove 27 20 formed in the breech plug B during rotation of the shaft 12' to impart a movement of translation to the latter. The cam groove 27 is of the variable lead type so that the desired translation of the plug will be effected in varying ratio to its rotation and vice versa. In connection with the plug's 25 translating structure just described it is pointed out that while the same is shown associated with a breech mechanism in which 30 the breech plug is rotated through the medium of a crank shaft and in which the energy stored in the swinging mechanism is utilized to initiate locking rotation of the plug and also in which unlocking rotation 35 of the plug will initiate opening movement of the carrier, it is in no way limited to use in connection with such type of mechanism. The crank shaft and the operator formed by the sleeve 18 and arms 19 and 20 with their 40 associated parts could be entirely dispensed with and the translating mechanism could then merely be constituted by a pivoted two-arm lever formed by the arms 14 and 25 and under such conditions the locking and 45 unlocking rotation of the plug effected through any suitable means would pivot the arms 14 and 25 in a manner that would effect the desired translation of the plug B for the purposes heretofore set forth. 50 The invention previously described constitutes the subject matter of our prior abandoned application Serial Number 403,866, filed August 16, 1920, allowed May 24, 1921.

We claim:—

55 1. In a gun, the combination of a carrier, a threaded breech plug mounted on the carrier for both motions of rotation and translation with respect to the carrier, a shaft rotatable on the carrier, and devices directly operated by rotation of the shaft, when the threads of the plug are disengaged from the threads of the screw box of the gun, to simultaneously rotate and translate the plug.

60 2. In a gun, the combination of a carrier,

a threaded breech plug mounted on the carrier for both motions of rotation and translation with respect to the carrier, a shaft rotatable on the carrier, and separate connections between the shaft and plug operating respectively, when the shaft is rotated with the threads of the plug disengaged from the threads of the screw box of the gun, to simultaneously rotate and translate the plug. 70 75

3. In a gun, the combination of a carrier, a threaded breech plug mounted on the carrier for both motions of rotation and translation with respect to the carrier, a shaft rotatable on the carrier, and separate connections between the shaft and plug operating respectively, when the shaft is rotated with the threads of the plug disengaged from the threads of the screw box of the gun, to simultaneously rotate and translate the plug, each of said connections having a portion fixed to the shaft. 80 85

4. In a gun, the combination of a carrier, a threaded breech plug mounted on the carrier for both motions of rotation and translation with respect to the carrier, a shaft rotatable on the carrier, means operated by rotation of the shaft to rotate the plug, and coacting elements on the plug and shaft operating to translate the plug when the latter is rotated by the shaft with its threads disengaged from the threads of the screw box of the gun. 90 95

5. In a gun, the combination of a carrier, a breech plug mounted on the carrier for both motions of rotation and translation with respect to the carrier, a shaft rotatable on the carrier, and crank arms on the shaft operatively connected with the plug to respectively rotate and translate the latter during rotation of the shaft. 100 105

6. In a gun, the combination of a carrier, a threaded breech plug mounted on the carrier for both movements of rotation and translation with respect to the carrier, a cam on the plug, a shaft rotatable on the carrier, means operated by rotation of the shaft to rotate the plug, and means on the shaft coacting with said cam to translate the plug when the latter is rotated by the shaft with its threads disengaged from the threads of the screw box of the gun. 110 115

7. In a gun, the combination of a carrier, a breech plug mounted on the carrier for both motions of rotation and translation with respect to the carrier, a rotatable shaft on the carrier, and devices simultaneously and directly operated by rotation of the shaft to effect rotation and translation of the plug in varying ratio. 120 125

8. In a gun, the combination of a carrier, a breech plug mounted on the carrier for both movements of rotation and translation with respect to the carrier, and separate connections between the shaft and plug op- 130

erating during rotation of the shaft to simultaneously produce the movements of the plug in varying ratio with respect to each other.

5 9. In a gun, the combination of a carrier, a breech plug mounted on the carrier for both movements of rotation and translation with respect to the carrier, a shaft rotatable on the carrier, means operated by rotation 10 of the shaft to rotate the plug, and elements on the plug and shaft coacting directly during rotation of the shaft to impart movement of translation to the plug in varying ratio to plug's rotative movement.

15 10. In a gun, the combination of a carrier, a breech plug mounted on the carrier for both motions of rotation and translation with respect to the carrier, a variable lead cam on the plug, a shaft on the carrier, 20 means operated by rotation of the shaft to rotate the plug; and means on the shaft coacting with said cam during rotation of the shaft to translate the plug.

11. In a gun, the combination of a carrier, 25 a breech plug mounted on the carrier for both motions of rotation and translation with respect to the carrier, means for imparting motion of rotation to the plug, and coacting elements between the plug and carrier for imparting motion of translation to the plug during said rotation and in varying ratio with respect thereto, each of said elements moving relatively to the carrier during said translation.

30 35 12. In a gun, the combination of a carrier, a breech plug mounted on the carrier for both motions of rotation and translation with respect to the carrier, means for rotating the plug, and coacting elements for 40 translating the plug, one of which is on

the plug and the other pivotally mounted on the carrier for oscillation.

13. In a gun, the combination of a carrier, a breech plug mounted on the carrier for both motions of rotation and translation with respect to the carrier, means for 45 rotating the plug, and coacting elements for imparting motion of translation to the plug during and in varying ratio to said rotation, one of said elements being on the 50 plug and the other pivotally mounted on the carrier for oscillation.

14. In a gun, the combination of a carrier, a breech plug mounted on the carrier for both motions of rotation and translation with respect to the carrier, means for 55 rotating the plug, a two arm lever pivoted on the carrier, connections between one arm of the lever and the plug whereby rotation of the latter will oscillate the lever, 60 and connections between the other arm of the lever and the plug whereby oscillation of the lever will translate the plug.

15. In a gun, the combination of a carrier, a breech plug mounted on the carrier for both motions of rotation and translation with respect to the carrier, means 65 for rotating the plug, a two-arm lever pivoted on the carrier, connections between one arm of the lever and the plug whereby rotation of the latter will oscillate the lever, 70 a cam on the plug, and a cam follower on the other arm of the lever coacting with said cam during oscillation of the lever to translate the plug. 75

In testimony whereof we hereunto affix our signatures.

HENRY J. STAMBAUGH.
GEORGE M. McCANN.
